CABLE GRIP

Edgar E. Kellems, New York, N. Y., assignor to
 Kellems Products, Inc., New York, N. Y., a
 corporation of New York

Application November 20, 1933, Serial No. 698,856

13 Claims. (Cl. 24—123)

This invention relates to a woven wire grip device in which crossing portions of the strands are relatively movable to permit lateral expansion through endwise compression or lateral compression through endwise extension so that when compressed endwise the woven fabric may be readily placed over and upon a cable or other object or the object may be drawn freely endwise therethrough from the receiving end toward the draft end with the assurance that when the endwise compression is relieved the device will automatically grip the surface of the object, particularly when extended endwise by force applied to either end or both ends of the woven fabric.

Devices of this character are particularly useful for drawing electric conductors or cables through underground conduits or along overhead supports but I have found similar devices may be used with equal efficiency for a large variety of other purposes through slight modifications of one or both ends of the woven wire fabric according to the use to which it is to be put and the main object of the present invention is to enable grips of this type to be adapted to a wide variety of uses without materially altering the process of weaving.

The gripping portions of devices of this character are usually woven in tubular form around and upon a suitable mandrel and one of the specific objects of the present invention is to divide the draft ends of the strands of the tubular fabric into one or more pairs of branches and to unite the outer ends of each pair of branches in such manner as to form U-shaped draft ends or heads and thereby to distribute the tensile strains upon the strands more evenly throughout the area of the woven wire tube than would be possible with the usual construction of draft eye in which the draft ends of the strands are bunched and bound together to form the draft eye.

Another specific object is to extend the strands of both branches of each pair around the U in overlapping relation and to bind the overlapping portions to each other by extra binding metal for firmly securing both branches to each other and thereby to not only strengthen the U-shaped end or draft head but also to further assure a more even distribution of the tensile stresses upon the strands of the woven wire tube and at the same time to secure a more uniform compression of all of the strands of the tube upon the work than has heretofore been practiced.

Another object is to reinforce the connected branches of each pair with a U-shaped metal casing or ferrule to prevent direct contact of the

draft device or anchorage with the adjacent portions of the strands and thereby to prolong the life of the draft head and strands.

A further object is to divide the strands of the cable-receiving end of the woven wire tube into two or more branches and to arrange each branch in the form of a loop for attachment to the anchorages or to the draft heads of other gripping devices if desired.

Other objects and uses relating to specific parts of the device will be brought out in the following description.

In the drawings:—

Figure 1 is a side elevation, partly broken away, of a tubular gripping device in which the strands of the draft end of the woven wire tube are divided into two branches having the strands of each branch returned along those of the other branch to form a U-shaped end which is reinforced by a U-shaped metal sleeve or ferrule, the portions of the strands of each branch adjacent the grip being bound together by extra metal ferrules.

Figure 2 is an enlarged sectional view taken along line 2—2, Figure 1, showing the overlapping portions of the strands at the return bends and their enclosing tube straightened.

Figure 3 is an enlarged detail sectional view taken on line 3—3, Figure 1, showing the manner of binding the ends of the strands to the adjacent branches.

Figure 4 is a side elevation, partly broken away, showing a modified form of U-shaped draft end formed by the return bends of the ends of both branches together with suitable ferrules for binding the ends of the strands to adjacent branches.

Figure 5 is an enlarged detail sectional view taken on line 5—5, Figure 4, showing the means for binding the overlapping ends of the strands of one branch upon the strands of the other branch.

Figure 6 is a side elevation, partly broken away, showing a longitudinally divided woven wire tube having its strands at one end divided and returned and the returned portions encased in a metal casing of binding wire or equivalent material; certain strands of the woven wire tube being extended and used for lacing the longitudinal edges of the tube together.

Figure 7 is a face view, partly broken away, of a flat woven wire fabric adapted to be bent in the form of a tube to bring its opposite longitudinal edges together, the draft ends of the fabric being divided to form two pairs of branches in which those of each pair are returned to form draft U's

and reinforced by a metal casing of wire or equivalent material, certain wires at the end of the fabric being shown for use in lacing the longitudinal edges of the fabric to each other.

5 Figure 8 is a side elevation, partly broken away, of a further modified form of my invention showing a single U-shaped draft head at one end and its opposite end divided into branches and its branches formed into loops.

10 Figure 9 is a further modified form of my invention showing a pair of U-shaped draft heads at one end and a plurality of, in this instance four, loops at its opposite ends formed by branches of the strands.

15 In all of the several modifications of my invention, the strands forming the gripping device per se are woven to form an open mesh tube in which the crossing portions of the strands are relatively movable to permit free radial expansion through 20 endwise compression of the tube and also to cause radial compression of the strands upon the work through endwise extension of the tube.

It is to be understood that these tubes will be made in different standard sizes as to diameter 25 and length according to the size or nature of the object to be supported or drawn endwise and that the diameter of each standard size will be slightly less than that of the object upon which it is to be placed to assure automatic compression of the 30 strands upon the work when the woven wire tube is drawn endwise from the draft end thereof.

The grip shown in Figures 1, 2 and 3 is adapted to be used more particularly for permanent installation of telephone and electric lighting cables 35 extending from the pole to the house where the service is to be given, but obviously may be used for drawing cables through underground conduits or along overhead supports and for any other purpose to which it may be applied and comprises 40 a woven wire tube 1 having the strands at its cable-receiving end continuous to form loops a similar to that shown and described in my Patent No. 1,670,543, May 22nd, 1928, the strands at the opposite or draft end of the tube being divided to 45 form a pair of branches 2, each containing a like number of strands arranged in transversely spaced relation to permit the cable or other object to pass from the receiving end between the branches and beyond the corresponding end of 50 the tube.

The strands of the branches adjacent the tube are preferably bound together by tubular metal ferrules 3 which are tightly compressed upon the strands to firmly hold them in relatively small 55 compact space near their junctions with the woven wire tube 1.

These branches are preferably extended a considerable distance beyond the ferrules 3 and the strands of each branch are preferably twisted 60 upon each other into rope form, the outer ends of the strands of each branch being inserted in opposite ends of a metal tube 4, preferably from end to end thereof so that the end of the strands of one branch may overlap upon those of the other 65 branch, the metal tube being then tightly compressed upon the overlapping ends of the strands and bent into reshaped form, thereby forming a U-shaped draft end or head 4 which serves to hold the ends of the branches in fixed overlapping 70 relation.

The ends of the strands are, therefore, dead-ended within the U-shaped tube 4 which serves as a means for attachment to any suitable draft device or anchorage whereby the woven wire tube 1 with the cable or other object therein may be 75

drawn endwise or supported upon any suitable anchorage.

Under this construction it will be evident that the tensile strains upon the several strands of the tube 1 will be evenly distributed throughout the 5 area of the tube and that when the later is placed over and upon a cable or other object and extended endwise, the strands of the tube will be firmly compressed against the periphery of said object throughout the length of the tube, there- 10 by assuring a more positive and reliable grip upon the object than would be possible if all of the strands at the draft end of the tube were bunched together and attached in that form to the usual draft eye. 15

Furthermore, the U-shaped loop or draft head 4 serves to hold the branches 2 in substantially parallel spaced relation and also to hold the overlapping ends of the strands of both branches in fixed relation and to firmly bind them together 20 by the compression of the tubular member 4 thereon, the dead-ending of the strands of both branches within the member 4 being clearly shown in Figure 2.

In the modified construction shown in Figures 25 4 and 5, the ends of the strands at the draft end of the woven wire tube 1 are also divided into opposite branches 2, the ends of the strands of each branch being preferably twisted into rope form for reinforcing purposes and extended some 30 distance outwardly beyond the tube 1 and returned along the other branch to form a U-shaped loop or draft head 4'.

The extreme ends of the strands of each branch, therefore, overlap upon the adjacent portions of 35 the strands of the other branch and are firmly clamped thereto by metal ferrules 3' similar to those previously described, each ferrule being firmly compressed upon the enclosed portions of the strands to hold them against relative lateral 40 or endwise movement.

In other words, the ends of the strands of each branch are dead-ended in the tubular ferrules 3' of the other branch, the dead-ending of the strands in said ferrules being shown more clearly 45 in Figure 5.

It will now be seen that the U-shaped end or head 4' of the construction shown in Figures 4 and 5 serves a purpose similar to the U-shaped head 4, Figure 1, in that the strains upon the 50 strands of the tubular member 1 incidental to the drawing of the tube with the cable or other object therein endwise is distributed over practically the entire area of the woven wire tube and causes said strands to be compressed firmly 55 against the periphery of the object throughout the length of the tube.

The U-shaped head 4, which is preferably made of copper, serves to hold the enclosed portions of the strands of both branches in fixed relation, 60 while the tubular ferrules 3 and 3', Figures 1 and 4, serve to hold the strands of each branch against separation one from the other the entire distance between the tubular body 1 and the U-shaped head 4 or 4' to further increase the firmness of grip of the woven wire tube upon the work when distended.

The modified construction shown in Figure 6 comprises a woven wire body portion 11 bent into tubular form to constitute what may be termed a split tube adapted to be wrapped around and upon the intermediate portion of a cable or other object when it is impracticable to place the same endwise over and upon the end of said object. 70

In this construction, the ends of the strands at 75

the draft end of the body 11 are extended and divided into separate branches 12 having an equal number of strands in each branch, the outer ends of the branches being continuous and bent into 5 the form of a loop which is encased in a U-shaped tubular metal head 13 consisting in this instance of wires wound firmly around and upon the branches for reinforcing purposes somewhat similar to that shown in Figure 1.

10 One of the wires as 14 of each branch, after being enclosed in the tubular casing 13, is left free and is extended toward the opposite ends of the fabric body 11 and is interlaced with the strands along the opposite edges of said body to 15 firmly hold said edges together and thereby to maintain the tubular form of the fabric after the latter has been wrapped around the object, the distal ends of the extension wires 14 being preferably twisted together to hold them against displacement from the loops.

In this construction, the free ends of the strands at the receiving end of the fabric tube 11 are bound together in pairs by copper or equivalent relatively short ferrules 15 which are firmly 20 compressed thereon to hold the strands of each pair in fixed relation and also to hold the several pairs of strands in spaced relation circumferentially so that the woven wire tube may be readily placed over and upon the object to be supported 25 or moved.

20 Figure 7 is a face view of a woven wire fabric for forming a longitudinally divided tube similar to that shown in Figure 6 except that the strands of the fabric are extended and divided into two 35 pairs of branches 12, the branches of each pair forming a U-shaped draft end encased in a corresponding U-shaped metal tube 13 similar to that shown in Figure 6.

That is, the strands of the branches of each 40 pair are extended continuously around the loop within its casing 13 to overlap upon the strands of the other branch of the same pair so that the overlapping portions of the loop may be bound together by the tubular casing 13 to hold them 45 in fixed relation to each other and to the casing and thereby to reinforce the strands of each loop.

In this construction, like that shown in Figure 6, one of the wires or strands entering one 50 end of each of the loops 13 at the corresponding longitudinal edge of the fabric is left free and is extended to form a lacing wire 14 so that when the fabric is wrapped around the object to be moved or supported the wires 14 may be interlaced with the strands adjacent the longitudinal 55 edges of the fabric and then twisted together at the ends as shown in Figure 6 to hold the lacing strands in operative position.

In the construction shown in Figure 7, the same 60 is composed of five strands, one of which forms the lacing wire 14 but aside from this lacing wire the strands of each branch 12 are divided into pairs and each pair is firmly bound together by a ferrule 16 between the loop 13 and the portion of the fabric body 11 to assist in distributing the tensile strains upon the strands of the tube and also to hold the strands of each pair 65 in fixed relation to each other when the fabric is wrapped around the object to be carried.

The ends of the strands at the receiving end 70 of the fabric are also bound together in pairs by tubular metal ferrules 15 similar to those shown in Figure 6.

The construction shown in Figure 8 comprises a woven wire tubular tube 1 in which the strands 75 at the draft end thereof are extended and divid-

ed into two branches 12, those of each branch being returned in overlapping relation to those of the other branch to form a U-shaped draft loop which is encased in a metal reinforcing tube 13 in a manner similar to that shown in Figure 6 5 in that the member 13 is made of wire wound tightly around the enclosed portions of the strands of both of the branches 12.

That is, the strands of both branches extend continuously through the member 13 and are 10 then interwoven to form the woven wire tube 1.

In this construction, the strands at the opposite site or receiving end of the woven wire tube 1 are also extended and divided into branches 18 and those of each branch are returned toward 15 the draft end to form separate loops 19 in which the ends of the strands of each branch overlap upon the remaining strands of the same branch and are firmly bound together by metal ferrules 20 each consisting in this instance of a wire 20 wound tightly around the overlapping portions of the strands to firmly hold the enclosed portions of the strands against relative endwise or lateral movement and thereby to hold the opposite portions of each loop in fixed relation. 25

It is now clear that one end of the woven wire gripping tube 1 is provided with a U-shaped draft end and that the other end is provided with two loops, the advantage of which is that it provides a plurality of points of suspension for supporting the cables horizontally or vertically, the loops 19 serving to hold the cable at different points so that if the object engaged by the grip should tend to slip back while being drawn or supported by the draft head 13, at least one of the loops 19 35 would hold the grip tightly upon the object.

The construction shown in Figure 9 comprises a woven wire tube grip 1 having the strands at its draft end extended and divided into separate pairs of branches 22, the branches of each pair 40 being extended continuously through a U-shaped tubular sleeve or head 13.

The ends of the strands, after being interwoven to form the open mesh tube 1, are divided into separate branches 24, each containing a plurality of, in this instance two, strands bound together by a tubular metal ferrule 25.

These strands extend some distance beyond their respective ferrules 25 to form loops 26, 26', and 27 and 27' of different lengths. 50

Each of the loops 26 and 26' includes two of the branches 24 and have their extreme ends inserted in opposite ends of tubular coupling members 28 and 28' which are preferably made of copper and arched outwardly to firmly bind the adjacent ends of the strands together. 55

The two strands of each of the other two loops 27 and 27' are divided and inserted in the opposite ends of outwardly arched tubes 29 and 29' which are compressed upon the adjacent ends of the strands to firmly couple them together. 60

It is now clear that the ends of the strands of each of the loops are dead-ended into their respective coupling members 28, 28', 29 and 29' which serve to support vertical cables permanently where it is not possible to get support on both sides of the cable at the same point. 65

The several modifications of gripping devices shown and described are adaptable for a wide range of uses in which the U-shaped end or ends 70 at the draft ends of the wire tube are important features in that they serve to distribute the tensile strains upon the strands throughout the area of the woven wire tube and afford a more positive and firmer grip upon the cable or other ob- 75

ject supported or moved thereby than heretofore practised.

Another feature of the U-shaped draft eye is that they prevent direct contact of the draft device with the strands of the woven wire fabric although in Figure 4, the strands which form the U-shaped end are continuous with those which form the gripping tube but are reinforced by their overlapping relation one upon the other on both sides of the branches.

Other modifications may be included within the scope of the invention and, therefore, I do not wish to limit myself to the exact construction shown and described.

What I claim is:

1. A gripping device of the character described comprising a plurality of wire strands interwoven to form an open mesh tube having its strands at one end grouped into separate branches, each branch being returned upon the other branch to form an open loop including both branches, and a U-shaped sleeve embracing the overlapping ends of both branches and maintaining the remaining portions thereof in spaced relation.
2. A gripping device of the character described comprising a plurality of wire strands interwoven to form a tubular grip open at one end and having its strands at the opposite end divided to form branches which are returned one upon the other to form an open loop, a tubular U-shaped sleeve embracing the overlapping ends of the branches, and a tubular metal ferrule embracing each branch adjacent the tubular grip and tightly compressed thereon, the distance between the opposite ends of the sleeve and the distance between the ferrules being approximately equal to the diameter of the tubular grip.
3. In a gripping device of the character described, a plurality of wire strands interwoven to form an open mesh tube having the strands at one end divided to form branches, the ends of said branches being returned one upon the other in overlapping relation to form a loop, a U-shaped sleeve embracing the overlapping ends of the branches and tubular metal ferrules, each embracing one of the branches adjacent the tubular grip.
4. In a gripping device of the character described, a plurality of wire strands interwoven to form an open mesh tubular grip, the strands at one end of the grip being divided to form branches, the strands of each branch being returned along the strands of the other branch to form a loop, and tubular ferrules embracing the strands of both branches adjacent the tubular grip and spaced apart diametrically a distance approximately equal to the diameter of said grip.
5. In a gripping device of the character described, a plurality of wire strands interwoven to form an open mesh tubular grip, the strands at one end of the grip being divided to form branches, the strands of each branch being returned along the strands of the other branch to form an open loop, and tubular ferrules each embracing the strands of one branch, said ferrules being spaced a distance apart corresponding approximately to the diameter of the tubular grip.
6. In a gripping device of the character described, a plurality of wire strands interwoven to form an open mesh tubular grip, the strands at one end of the grip being divided to form branches each returned upon the other to form an open loop, and tubular ferrules, one for each branch and each ferrule embracing the strands of its cor-

responding branch between the open side of the loop and tubular grip.

7. In a gripping device of the character described, a plurality of wire strands interwoven to form an open mesh fabric adapted to be wrapped around and upon the object to be supported or moved, certain strands of the fabric being left free and adapted to be interlaced with the strands along opposite edges of the fabric to bind the fabric around and upon the object.

8. In a gripping device of the character described, a plurality of wire strands interwoven to form an open mesh fabric, the strands at one end of the fabric being divided to form branches, and a U-shaped sleeve connecting said branches, certain wires of the branches being left free and adapted to be interlaced with the strands along opposite edges of the fabric to draw the same together around the object to be gripped.

9. In a gripping device of the character described, a plurality of wire strands interwoven to form an open mesh tubular body having draft and receiving ends and having the strands at both ends of the body divided into branches, the strands of said branches being extended substantially beyond the respective ends of the body and bent into the form of loops, the loops at the receiving end being capable of receiving an object to be supported.

10. In a gripping device of the character described, an open mesh woven wire tube having extension strands at one end divided into groups, the strands of each group being returned upon those of the other group and secured thereto to form a loop having its ends spaced apart a distance approximately equal to the diameter of the woven wire tube for equal distribution of tensile strains along diametrically opposite sides of the tube.

11. In a gripping device of the character described, an open mesh woven wire tube having extension strands at one end divided into groups, the strands of each group being returned upon those of the other group and secured thereto to form a loop, and a U-shaped sleeve tightly embracing the returned portion of the loop and having its ends spaced apart a distance approximately equal to the diameter of the woven wire tube.

12. In a gripping device of the character described, an open mesh woven wire tube having extension strands at one end divided into groups, the strands of each group being returned upon those of the other group and secured thereto to form an open loop, and separate ferrules each tightly embracing the strands of one of the groups between the open end of the loop and woven wire tube, said ferrules being spaced apart a distance approximately equal to the diameter of the woven wire tube.

13. In a gripping device of the character described, a plurality of wire strands interwoven to form an open mesh body portion adapted to be placed in surrounding gripping relation with a tubular member, said body portion having extension strands at one end thereof divided into groups, the strands of each group being returned upon those of the other group and secured thereto to form a draft loop, said loop having the portions adjacent the body portion extending therefrom in spaced substantially parallel relation for equalizing the tensile strains upon the several strands of the device.
